UNITED STATES PATENT OFFICE.

JAMES M. BUTCHER, OF CHICAGO, ILLINOIS, ASSIGNOR, BY MESNE ASSIGNMENTS, TO MARSHALL DOBBINS & CO., OF CHICAGO, ILLINOIS, A CORPORATION OF ILLINOIS.

PORTABLE BURGLAR-ALARM.

1,310,941.

Specification of Letters Patent. Patented July 22, 1919.

Application filed September 12, 1914. Serial No. 861,365.

To all whom it may concern:

Be it known that I, JAMES M. BUTCHER, a citizen of the United States, residing at Chicago, in the county of Cook and State of Illinois, have invented certain new and useful Improvements in Portable Burglar-Alarms, of which the following is a specification.

This invention relates to improvements in alarms, and more especially to that type of alarm which I term a portable alarm, and which may be conveniently carried by travelers for use in warning them of attempted entrance into their rooms. More particularly my invention comprises an alarm adapted to be attached to the shank of a door knob, so that the turning of said shank in either direction will cause an alarm to be given. A further feature of my invention relates to the novelty and simplicity of the structure, whereby the alarm is inexpensive in cost and durable and efficient in use.

These and other objects of my invention will be more particularly set forth in the following specification, taken in connection with the accompanying drawings, in which I have illustrated a specific form of my invention.

30 In the drawings—

Figure 1 is a front elevation of my improved alarm suspended from a door knob shank, which is shown in section.

Fig. 2 shows a rear elevation of the bell and lower portion of the standard by which it is supported.

Fig. 3 shows a side elevation of my improved alarm suspended from the shank of a door knob;

Fig. 4 shows an enlarged front elevation of the lower portion of the clamp member and of the means by which the actuating member is operated;

Fig. 5 shows a plan view of the clamping shoe.

Referring to the drawings, the numeral 10 designates a bell which may be employed to give the alarm. This bell is of a type well known, in which there is a check member operating to normally prevent operation of the bell, and upon the release of which the bell is permitted to ring, as I term it, continuously, that is for a considerable period

of time. A bell of the type shown is spring-actuated, and is wound up by rotating the 55 cap portion of the bell with respect to its base or casing, but since I do not wish to be limited to any particular form of bell, I give no detailed description thereof.

The operating or check member of the 60 bell is designated by the numeral 11, and is in the form of a push button, which, when pressed inwardly, causes the bell to ring, but which automatically returns to normal position to prevent the bell from ringing 65 when the pressure thereon is removed.

A standard or depending link 12 serves as a support for the bell, and its lower hooked extremity—shown in Fig. 2—is provided with right angularly disposed slots 13 and 70 14, which are adapted to be engaged by screws 15 which enter suitable threaded apertures in the wall of the bell casing. These slots permit a variation of the position of the bell with respect to the standard 75 and associated parts, for a purpose to be hereinafter set forth.

The standard 12 has its upper extremity 16 angularly disposed with respect to the longitudinal axis thereof, and the rivet 17 80 engages the portion 16 for the purpose of making a pivotal connection with the lower portion 18^a of the clamp 18. This lower portion of the clamp member is provided with an inwardly turned parallel lip 18^c, 85 between which and the portion 18^a the standard is supported. This clamp member is arcuate in form, as clearly shown in Fig. 1, and is provided at its upper end with an enlarged head which is engaged by the 90 thumb screw 19. The lower extremity of the thumb-screw forms a pivotal connection with a clamping shoe 20, which is slotted at one extremity to slide upon the body of the clamp member 18 and is provided with 95 a substantially curved surface beneath the thumb screw. This curved surface of the shoe is adapted to engage the shank 21 of a door knob 22, as clearly shown in Figs. 1 and 3, and when the thumb-screw is moved 100 downwardly with respect to the clamp member the shank will be tightly gripped between the shoe and the portion 18^a of the clamp member, which is provided with a notch 18^b on its upper side for engagement 105 with the lower side of said shank. By this

means the clamp member can be rigidly connected to the shank of a door knob so as to rotate therewith.

While I have shown the clamp as constructed to engage the latch-operating shaft, it might readily be shaped to engage the knob instead.

The bell is actuated by what I term an actuating member 24, which is in the form 10 of a lever co-extensive with and pivoted on the standard 12 by means of a rivet at the point 25. The lower portion of the actuating member extends outwardly in the form of an arc 26 adjacent the side of the 15 bell in the form of construction here shown, and terminates in an angularly disposed lip 27, which is arranged to engage the operating or check member 11 of the bell. At its upper extremity the actuating member is 20 provided with a rounded lateral surface 28, which is adapted to coact with a cam surface 29 on the lip 18° above described. When the alarm is in its normal position it will be apparent that the weight of the bell will 25 maintain the standard and actuating members in substantially vertical positions, and when the alarm is in this normal position the curved surface 28 of the actuating member will engage the concave portion 29^a of 30 the cam 29. When the shank 21 is rotated in either direction, however, the clamp member 18 will be carried around therewith and the weight of the bell—which tends at all times to maintain the standard in a vertical position—will cause said standard to swing about the pivot 17, whereupon the curved portion 28 of the actuating member will be caused to pass outwardly from the concave portion 29^a of the cam surface and engage 35 one or the other of the inwardly projecting convex portions 29^b of said cam. This movement of the portion 28 of the actuating member will rotate said member about the pivot 25 and cause the lip 27 to press 40 inwardly on the operating or check member 11, and thereby cause the bell to ring. Variations in the sensitiveness of the bell may be secured by loosening the screws 15 and adjusting the bell on the standard so as to 45 vary the initial pressure of the lip 27 on the check member 11.

From the above description it will be apparent that I have provided a simple and efficient alarm, which is capable of being attached to the shank of any door-knob, and 50

which will be actuated to give an alarm upon the rotation of the door knob in either direction.

While I have shown a particular form of construction and a particular arrangement of the various parts with respect to the bell, it will be understood that both the construction and arrangement of parts may be altered in various ways without departing from the spirit of my invention as defined 65 by the appended claims.

I claim:—

1. An alarm comprising a bell having an operating member, a standard by which said bell is carried, a clamp member to which the standard is pivoted and which is adapted to be attached to a supporting member, an actuating member pivoted on said standard arranged to engage the operating member and the clamp member, and means to vary the relative normal relation of said actuating and operating members. 75

2. An alarm comprising a bell having an operating member, a standard by which said bell is carried, said operating member being movable transversely to the principal axis of said standard, a clamp member to which the standard is pivoted and which is adapted to be attached to a supporting member, and an actuating member pivoted on said standard and arranged to be actuated by said clamp member upon relative movement of said clamp member and said standard, said actuating member being provided with an offset portion adapted to coact with said operating member to actuate the same. 80

3. In a device of the class described, the combination of a clamp adapted for attachment to a latch operating shaft, said clamp including a cam, a link pivoted to the clamp, a bell secured to the extremity of the link, a lever pivoted to the link and adapted to actuate the bell, said lever having a cam for coöperation with the cam on the clamp 95 whereby said lever is oscillated in either direction with respect to the link when the clamp is moved. 100

In testimony whereof, I have subscribed my name.

JAMES M. BUTCHER.
